UNITED STATES PATENT OFFICE.

GEORGE G. CONVERS AND ARTHUR B. DE SAULLES, OF SOUTH BETHLEHEM, PENNSYLVANIA.

APPARATUS FOR PRODUCING ZINC-DUST.

SPECIFICATION forming part of Letters Patent No. 727,297, dated May 5, 1903.

Application filed September 14, 1898. Serial No. 690,913. (No model.)

To all whom it may concern:

Be it known that we, GEORGE G. CONVERS and ARTHUR B. DE SAULLES, citizens of the United States, residing in South Bethlehem, 5 in the county of Northampton and State of Pennsylvania, have invented certain new and useful Improvements in Apparatus for Producing Zinc-Dust; and we do hereby declare the following to be a full, clear, and exact description of the invention, such as will enable others skilled in the art to which it appertains to make and use the same.

In an application of even date herewith, Serial No. 690,911, we have described a method 15 of obtaining from zinc-bearing material metallic zinc in the finely-divided condition known as "zinc-dust" or "blue powder" and have shown therein two different forms of apparatus adapted for the practice of said 20 method. The present application relates generally to said apparatus, and more specifically to one of the forms thereof.

In the accompanying drawings, Figure 1 represents the apparatus, partly in section, 25 and partly in elevation. Fig. 2 represents a vertical sectional view thereof.

Similar letters of reference indicate similar parts throughout both views.

Referring to the drawings, A indicates the 30 basal portion of the furnace, having the fuel-chamber *a*, grate-bars *b*, ash-pit *c*, and arch *B*, through which arch the products of combustion pass by suitable openings, as *w*, to the chimney-stack *D*. Upon the side walls of 35 the fuel-chamber rest the open-ended "cannon" *f*, and above them are located the zinc-distilling retorts *n*, the function of the cannon being to distribute the products of combustion about the sides of the retorts and to prevent 40 the retort-bottoms from being subjected to too high a heat. The retorts *n*, as shown, rest upon refractory tiles or bricks built up from the base *A* of the furnace and are arranged at different heights in series, as shown. 45 Above the retort-chamber is provided with the arch *B*, and the entire furnace is strengthened and bonded by buckstays and cross-ties, as shown.

The retorts *n* have each an exit-opening *m* 50 for the zinc-vapors and are charged from the opposite end, which is shown in Fig. 2 as luted

up. The corresponding wall of the furnace is removable in order to obtain access to the retorts and cannons.

Each double vertical series of retorts 55 communicates through the vapor-exit openings *m* with a corresponding collecting-chamber *C*, forming part of the furnace structure and immediately adjacent to the muffles, so that the muffles open directly into the collector, 60 thereby avoiding danger of intermediate liquefaction of the zinc-vapors before they have had an opportunity to expand within the chamber. Each chamber is provided in its front wall with a series of openings adapted 65 to be closed by slides or valves *z*⁵, said openings being located opposite the retort-openings *m*. At the lower portion is located an opening closed by a slide *z*⁴ for removing the zinc-dust resulting from the operation, 70 and at the top is located a safety-valve in the form of a slip-cover or lid *x*², having a small vent-hole *n*', as shown, of about one inch in diameter.

The retorts or muffles are charged with the 75 zinc-bearing material from the rear end—*i. e.*, from the end opposite to that at which the collectors are located. At the outset small sheet-iron cones (one of which is indicated in dotted lines in Fig. 2) are connected 80 to the retort-openings for the purpose of catching the oxid of zinc that is given off at the beginning of the operation. As soon as the color of the deposit at the outer end of the sheet-iron cones indicates the formation 85 of zinc-dust the cones are removed and slides *z*⁵ are closed. The distillation is then continued until the fumes escaping through the vent-holes *n*' at the top of the collectors begin to show again the presence of oxid of zinc. 90 The sheet-iron cones or prolongs are thereupon again placed in communication with the retorts, so as to catch, as in the first instance, the oxid of zinc that is being formed, thereby preventing its admixture with the 95 zinc-dust already collected. The rear end of the retorts or muffles are then opened, the spent charge is withdrawn, and the muffles are freshly charged. The operation is then repeated, although in general the zinc-dust 100 from each charge is removed from the collector before the fresh charge begins to distil.

The construction of apparatus described has the advantage of dispensing with any intermediate joint between the retort exit-openings and the collecting-chamber, and therefore absolutely insures against the possibility of the formation of melted zinc at that point. Moreover, it enables one collector to be used for muffles located one above the other, a matter of difficulty if a separate sheet-iron collector having a rear wall were employed, because of the fact that in adjusting such sheet-iron collector to the several muffles it is found in practice that it is almost impossible to make the various nipples register exactly with the corresponding openings in the casing and make reliable gas-tight joints.

Having thus described our invention, what we claim is—

1. An apparatus for the recovery of zinc-dust or blue powder, comprising a plurality of muffles arranged at different heights, a furnace for heating the same externally, and an expansion-chamber common to the series, the rear wall of the expansion-chamber being formed by the front wall of the combustion-chamber, thereby providing direct and jointless communication between the muffles and expansion-chamber, said expansion-chamber

being of such capacity relatively to the retorts as to immediately expand and solidify the zinc-vapors into zinc-dust; substantially as described.

2. An apparatus for the recovery of zinc-dust or blue powder, comprising a plurality of muffles arranged at different heights, a furnace for heating the same externally, and an expansion-chamber common to the series, the rear wall of the expansion-chamber being formed by the front wall of the combustion-chamber, thereby providing direct and jointless communication between the muffles and expansion-chamber, said expansion-chamber being of such capacity relatively to the retorts as to immediately expand and solidify the zinc-vapors into zinc-dust, a series of openings in the front wall of the expansion-chamber opposite the muffle-exit openings and doors or slides for said openings, substantially as described.

In testimony whereof we affix our signatures in presence of two witnesses.

GEORGE G. CONVERS.

ARTHUR B. DE SAULLES.
